UNITED STATES PATENT OFFICE.

CARL C. HARRIS, OF ORANGE, AND DESRIE A. STOWELL, OF GARDNER, MASSACHUSETTS, ASSIGNORS TO SIMPLEX TIME RECORDER COMPANY, OF GARDNER, MASSACHUSETTS, A CORPORATION OF MASSACHUSETTS.

WORKMAN'S TIME-RECORDER.

1,095,158.

Specification of Letters Patent. Patented Apr. 28, 1914.

Application filed January 18, 1913. Serial No. 742,771.

To all whom it may concern:

Be it known that we, CARL C. HARRIS and DESRIE A. STOWELL, both citizens of the United States, and residents of Orange, 5 county of Franklin, State of Massachusetts, and Gardner, county of Worcester, State of Massachusetts, respectively, have invented an Improvement in Workmen's Time-Recorders, of which the following description, 10 in connection with the accompanying drawing, is a specification, like characters on the drawing representing like parts.

This invention relates to apparatus for recording on a suitable card or other check 15 certain desired times, such as the time a workman enters or leaves his place of employment, the time of beginning and ending a certain piece of work, etc., each employee having his individual card. The 20 card is used for any convenient period, and the records on the card determine the compensation due the workman for the given period. In our present invention, which relates to that type of time-recording apparatus 25 in which the proper positioning of the card to receive the desired record is effected by the employee, we are not concerned with the particular character or construction of the recording mechanism, as the same 30 may be of any suitable or well known structure arranged for manual operation. Time recorders of this general type are provided with an indicator or pointer fixed with relation to the record-making point of the apparatus, and by which the employee positions the card for getting "in," "out" or 35 other record impressed thereupon, the cards having appropriate spaces thereon marked "In," "Out," etc. Such recorders have a common objection attendant upon their use, 40 namely, the making of many errors in recording when located in dark or poorly lighted places, and by persons of limited intelligence. In many instances the printed 45 matter on the card is hard to read, owing to insufficient light, and if the employee is of limited intelligence the printed matter on the card is not a sufficient aid, and poor records are made, one overlapping another; or 50 an "in" record will be made when an "out"

record is desired, or vice versa. This is most objectionable, for it makes the computation of the employee's time a difficult matter, and errors are certain to result in allotting the compensation.

55

In our present invention we use a record card having a desired or pre-arranged series of record-receiving spaces visually differentiated by strongly contrasted indicia, or index areas, as we have termed them, and the 60 card-positioning indicator has displayed upon it a set of strongly contrasted indicia or index areas corresponding characteristic 65 to those upon the card. That is, if for instance the "in" record-receiving spaces on the card are all provided with light index areas, and the "out" spaces are all provided with dark index areas, then the indicator is provided with a set of light and dark index areas, the former for "in" 70 and the latter for "out" records. By this arrangement the employee is greatly assisted in properly positioning his card for record by the visual relation between a given index area on the card and the corresponding index area on the indicator. The employee, even if illiterate or not very intelligent, very quickly associates a dark index area on his card with one kind of record, and a light index area with another kind of 75 record, the corresponding index areas on the card and indicator being clearly visible even if the light is so poor as to make it difficult to read printed matter on the card, and the positioning of the card becomes a matter of 80 observing strongly contrasted and boldly displayed index areas instead of an attempt to read words on the card printed necessarily in rather small type.

The novel features of our invention will 85 be fully described in the subjoined specification and particularly pointed out in the following claims.

Figure 1 is a front elevation of a workman's time-recorder embodying one practical form of our invention; Fig. 2 is a face view, centrally broken out to save space of one of the individual cards or checks to be used in connection with our present invention; Fig. 3 is a perspective view, much en- 95 100

larged, of the card-positioning indicator and a portion of a card positioned for the marking of a record thereon; Fig. 4 is a vertical sectional detail, to be referred to, taken on the line 4—4, Fig. 1.

Referring to Fig. 1, the casing 1 contains the operative parts of the mechanism, inclosed therein, and is provided with a time movement or clock having an exposed dial 12 and hands, as at 2, as is usual in time-recorders, and we have indicated by dotted lines any suitable record-making means comprising usual printing wheels 3 and a hammer or platen, as 4, one record-making means 13 being driven and controlled through the flexible shaft 5 connected by suitable gearing 6 with the minute-hand arbor of the time-movement. The card to receive the record thereupon is inserted edgewise in a card-receiver, shown as comprising a horizontal shelf 7 extended along the front of the casing and having a top 8 which partly overhangs the shelf, the latter being apertured at 9, Fig. 4, above the platen 4 and below an opening 8^x in the top 8. When the card is inserted in the receiver it lies between the printing or marking wheels 3 and the platen 4, the rear edge of the card being adapted to rest against the back 10 of the card-receiver, so that when the employee actuates the record-making means, as by depressing a handle 11 at the front of the casing, the printing set and the platen are brought toward each other, and the record is impressed upon the part of the card between the openings 8^x and 9. Inasmuch as record-making devices of this general character are well known and are made in many forms no further description or illustration is deemed necessary herein, as the record-making device *per se* forms no part of our present invention.

The general character of the record-card or check used is shown in Fig. 2, and it has at its upper end a suitable heading for the name of the employee, and other desired data, and at the lower end blank spaces are provided for summation of time, rate, etc. The body of the card is divided by a plurality of sets of transverse and longitudinal lines into the desired spaces, and herein we have shown the card divided longitudinally and centrally to present on the one side "regular time" and on the other side "extra time." At each side of the central division line is a longitudinal column of spaces for the days of the week, and each day space extends lengthwise of a series of transverse record-receiving spaces, indicated at 12, four of such spaces being herein shown for each day space. This is for the purpose of providing for the "in" and "out" records for the morning and afternoon of each day, as will be apparent. Between the long "day" spaces and the corresponding transverse

spaces 12, (which latter are arranged in a longitudinal column) we provide a column 13 of index areas for the record-receiving spaces 12, and we have shown said index areas as a series of alternating light and dark rectangles. Preferably each index area has printed thereon the word "In" or "Out," the lettering being dark in a light area, and light in a dark area, and herein we have shown the light index areas as arranged for the "in" records, that is, adjacent the spaces for recording the time the employee came to his work, while the dark index areas are arranged for the "out" records. While the lettering can be readily seen and read, if the light be good, the two sets of index areas contrast so strongly with each other that they can be easily distinguished even in a very poor light, and when the lettering cannot be read. If the card-receiver is provided with an indicator 14 fixed upon the exterior of the casing with relation to and contiguous the record-making point, so that the workman can position his card properly for the marking thereupon of the desired record, the card can be placed by bringing the space thereon in which the record is to be marked opposite the tip of the indicator, as in Fig. 3. When the light is good it is a simple matter to position the card with a space marked "In" or "Out," as the case may be, opposite the indicator, and then the handle 11 is actuated to effect the marking of the record. If the light is poor, however, and the printing on the card is hard to read, or if the employee is not very intelligent, the placing of the card properly becomes very frequently a matter of chance or guesswork, with the result that uncertain, overlapping, or absolutely wrong records are often made. We obviate reliance upon the accurate and intelligent reading of printed matter on the card by using the strongly contrasting indicia thereon, hereinbefore described, so that the positioning of the card in the receiver is merely a choice between a set or series of highly characteristic and distinct indices on the card, such as the light and dark index areas described herein. Even in a very poorly lighted place it is an easy matter for the employee to distinguish between a light index area and a dark one, and should he be blessed with very limited intelligence he would realize that each index area stood for a predetermined kind of record. In order, however, to further assist the employee in readily positioning his card correctly for the desired record to be made thereon we have widened out the head or upper part 125 of the indicator at 15, and display thereon indicia correspondingly to the set on the card, but preferably considerably larger in size. Such indicia are herein shown as two large and adjacent rectangu- 130

lar index areas 16, 17, Fig. 3, strongly contrasted by making one light and the other dark, and as the dark index areas on the card indicate "out" records we display in light letters the word "Out" on the dark rectangle 17, and display in dark lettering the word "In" on the light index area or rectangle 16. The order, or special arrangement, in which the index areas appear on the indicator is not of material moment so long as the indicia on the indicator correspond characteristically with those upon the card, as the object of the indicia on the head of the indicator 14 is to facilitate, by the visual relation between a given index area on the card and the corresponding index area on the card, the positioning of the card in the card-receiver by placing the proper record-receiving space on the card at the record-making point. As the indicia on the indicator are so much larger than those on the card the former can be read easily even in a very poorly lighted room, whereby if an employee is in doubt as to the actual significance of the contrasting indices he can easily satisfy himself by reading the large and plain lettering on the indicator.

While it is not absolutely necessary to do so, we prefer to make that part of the indicator 14 which is nearest the positioned card substantially the width of one of the index areas, as is shown in Fig. 3, for the employee has then only to position the desired characteristic index area squarely with relation to the pointer to insure the desired record in the proper space on the card. The back or stop 10, Fig. 4, is so located that when the card is placed in the card-receiver with the rear edge of the card against the stop 10 the series of index areas in the column 13 of the card will all be exposed beyond the plane of the front wall 1^x of the casing and upon which we have shown the indicator 14 mounted fixedly. The card is moved longitudinally in the receiver, upon the shelf 7 thereof, until the proper index area is brought opposite the lower end of the pointer, whereupon the apparatus is operated to make the record. As each set of spaces 12 for any given day is grouped opposite and adjacent the longitudinal "day" space it is very easy to distinguish the spaces for one day from those for another day, so that no confusion on this account is liable to arise, and the strongly contrasting index areas of the record-receiving spaces of a day set are readily distinguished by the employee as hereinabove pointed out.

Our invention is not restricted to the precise construction and arrangement herein shown and described as the same may be modified or re-arranged in different particulars by those skilled in the art without departing from the spirit and scope of our invention as set forth in the annexed claims.

Having fully described our invention, what we claim as new and desire to secure by Letters Patent is:

1. In a workman's time recorder, in combination, time controlled means to make a record, a receiver adapted to receive temporarily a card having a series of record-receiving spaces arranged in a predetermined order and visually differentiated by strongly contrasted index areas, and a card-positioning indicator by reference to which the card may be positioned manually in the receiver for the impress of the record in the different spaces, said indicator being fixedly mounted with respect to the record-making point and having displayed upon it a plurality of strongly contrasted index areas corresponding characteristically to those upon the card, whereby the positioning of a card in the receiver is facilitated by the visual relation between the index areas on the card and indicator. 75

2. In a workman's time recorder, in combination, a casing, time controlled means therein to make a record, a receiver adapted to receive temporarily a card having "in" and "out", record receiving spaces arranged alternately one below the other with adjacent spaces visually differentiated by contiguous light and dark index areas, a card positioning indicator by reference to which a card may be positioned manually in the receiver to receive a record in the desired space, said indicator being mounted upon the exterior of the casing adjacent the card receiver and fixed with respect to the record-making point and having displayed thereupon adjacent light and dark index areas corresponding to the "in" and "out" indices upon the card, corresponding indices on the card, and an indicator facilitating the placing of a card in the receiver with the desired record-receiving space on the card in position to receive a record. 90

3. In a workman's time recorder, in combination, an inclosing casing provided with time controlled means to make a record, a receiver adapted to receive temporarily a card having a series of spaces for receiving records of different kinds visually differentiated from each other by strongly contrasted index areas adjacent the inner ends of the spaces, and a card-positioning indicator by reference to which the card may be accurately positioned manually for the impress of the record in the proper space, said indicator being mounted exteriorly on the casing and fixed with respect to the record-making point and having a part thereof close to the mouth of the receiver and of a width substantially equal to that of a record-receiving space on the card, the indicator having also displayed upon it, a set of strongly contrasted enlarged index areas corresponding characteristically to those upon the card, the vis- 110

ual relation established between a particular index area upon the card and the characteristically corresponding area displayed on the indicator facilitating the accurate positioning of the card in the receiver for the reception of the desired record in the proper space thereupon.

5. In a workman's time recorder, in combination, a casing, time controlled means therein to make a record, a card receiver within which a record card may be manually positioned to receive a record, and a card-positioning indicator, said card having record-receiving spaces marked thereon and 10 said indicator having a part thereof adjacent said card receiver of a width substantially equal to one of said spaces, said indicator also having displayed thereon a set of 15 strongly contrasted index areas.
15. In a workman's time-recorder, in combination, a casing having inclosed therein time controlled means to make a record, a 20

card-receiver arranged horizontally in the casing and having an elongated opening for the reception of a record card and permitting manual lengthwise adjustment therein relative to the record-making point, a stop to engage the rear edge of the card and limit the distance the card can be inserted in the receiver, and an indicator mounted on 25 the casing above the mouth of the receiver, and fixed with respect to the record-making point, said indicator having displayed thereupon characteristically different and strongly contrasted indicia to correspond with similar indicia on the card.

In testimony whereof, we have signed our names to this specification, in the presence of two subscribing witnesses.

CARL C. HARRIS.
DESRIE A. STOWELL.
